WASTE CAN

Adj. F. Fervier, Wellsburg, W. Va., assignor to Eagle
Manufacturing Company, Wellsburg, W. Va., a corporation of West Virginia

Filed June 5, 1961, Ser. No. 65,447

Term of patent 14 years

(Cl. D58—17)

FIG. 1 is a top plan view of a waste can, embodying
my new design;

FIG. 2 is a side elevational view;

FIG. 3 is a sectional view thereof taken on the line
III-III of FIG. 1; and

FIG. 4 is a rear elevation of the can.

I claim:

The ornamental design for a waste can, as shown.
